UNITED STATES PATENT OFFICE.

ADOLF TELLSCHOW, OF BERLIN, GERMANY.

MACHINE FOR MAKING ENVELOPS OR THE LIKE.

SPECIFICATION forming part of Letters Patent No. 747,021, dated December 15, 1903.

Application filed October 20, 1903. Serial No. 177,803. (No model.)

To all whom it may concern:

Be it known that I, ADOLF TELLSCHOW, engineer, a subject of the German Emperor, residing at 27 Grünauerstrasse, Berlin, Germany, have invented certain new and useful Improvements in Machines for Making Envelops or the Like; and I do hereby declare the following to be a full, clear, and exact description of the invention, such as will enable others skilled in the art to which it appertains to make and use the same.

In the specification to application for Letters Patent, dated June 17, 1903, Serial No. 161,842, was described a matrix-frame for envelop-making machines and the like composed of four separate angular pieces or sections forming between them the mold or opening through which the piece of material for forming the envelop or the like was pressed by a die. These four pieces or sections have each a bolt-like projection that can slide in a tubular guide, such motion being produced by a pin on the bolt being engaged in the cam-shaped slot in an annulus or ring, by the rotation of which the four angular pieces are consequently moved toward or away from each other.

The present invention relates to means for actuating the four folding-flaps that are situated below the matrix-frame and which have to be adjusted in position in a corresponding manner to the adjustment of the four parts of the matrix-frame. According to this invention the said folding-flaps are adjusted by a prescribed motion dependent upon the motion of the parts of the matrix-frame, for which purpose the said setting ring or annulus *i* is combined with a lower setting-ring, which is also provided with cam-slots, with which are engaged pins carried by guide-bolts projecting from the fixed parts of the hinges of the folding-flaps. Thus when the setting-ring *i* is turned so as to move the parts of the matrix-frame to or from each other the lower setting-ring is moved simultaneously, so as to shift the fixed parts of the folding-flap hinges in a corresponding manner.

A construction according to the present invention is shown on the accompanying drawings, in which—

Figure 1 shows a plan, and Fig. 2 a side view, partly in section.

i, Fig. 1, are the two halves of the above-mentioned setting-ring having the cam-slots *k*, with which engage the pins *e* on bolts *d*, sliding radially in tubular guides *g*, Fig. 2. Below the ring *i* is the cylindrical piece *f*, on the lower end of which is mounted the annulus or ring *l*, which has four cam-slots *2*, Fig. 60 *1*, similar to those of ring *i*. This ring *l* is fixed rigidly to *i* by means of pillars *3*, so that both rings move together.

Below the ring *l* is a cylindrical piece *4* similar to *f*, on which are formed four radially-projecting guide-tubes *5*. In these guides slide bolts *6*, having vertical pins *7*, which engage with the slots *2* of the ring *l*, so that on turning the latter the bolts *6* will be shifted either inwardly or outwardly, and this motion serves, as above stated, to shift the folding-flaps *8* simultaneously with the sections *a* of the matrix-frame. The folding-flaps *8*, as shown at Fig. 2, do not consist of angular pieces like the parts *a* of the matrix-frame, but only have a flat surface, each of which corresponds to one of the four sides of the matrix-frame. While, therefore, the parts of the latter require to move in a diagonal direction relatively to the opening of the frame, the four folding-flaps move, respectively, parallel to one side of the said opening. In consequence hereof the guide-bolts *6* lie at an angle of forty-five degrees to the guide-bolts *d* of the matrix-frame. The setting-ring *i* is divided into two separate halves, so that on moving them apart rectangular forms for the envelops can be produced irrespective of the shifting of the angular pieces *a* relatively to each other, and in order to retain this advantage the second ring *l* also requires to be divided, this being effected, as shown in the lower part of Fig. 2, by making the division through two of the slots *2*.

The adjusting of the folding-flaps *8* by means of the guide-bolts *6* is effected as follows: On the under side of the table *9*, Fig. 2, of the machine there are fixed tubular guides *10*, similar to the guides *5*, in which slide guide-bolts *11*. The outer end of each of these bolts *11* is connected by a flat bar *12* with the outer end of the corresponding bolt *6* by

means of screws, so that each pair of bolts 6 and 11 must move together. As shown at Fig. 2, the bolts 11 carry on their inner ends one of the fixed parts of the folding-flap hinges, to which the folding-flaps proper, 13, are pivotally connected, the flaps 13 being actuated in any suitable manner.

The action of the above-described arrangement will be readily understood. If the ring 1 be turned, the ring 1 turns with it. The pins 7 move in the slots 2 of the ring 1 and carry the bolts 6 with them, which in their turn move the bolts 11 and with them the hinge parts 8 of the folding-flaps. If the form of the envelop to be folded is to be altered by moving apart the two halves of the ring 1, the pins 7 (shown at top and at bottom of Fig. 1) would lose their guiding-support, because the two halves of the ring 1 would also be moved apart, and consequently the two corresponding slots 2 would be opened out. In order, notwithstanding this, to insure the correct position of the two corresponding folding-flaps, their bolts 6 are secured to their tubular guides 5 by means of small setting-screws 14 or the like.

Having now particularly described and ascertained the nature of my said invention and in what manner the same is to be performed, I declare that what I claim is—

1. The combination of a matrix-frame for an envelop or similar machine consisting of a plurality of sections adjustable relative to each other to vary the size of the opening in the frame, means for simultaneously adjusting said sections and maintaining them in adjusted position, a plurality of folding-flaps situated below the matrix-frame and means for adjusting said folding-flaps simultaneously with said sections and maintaining them in adjusted position, substantially as described and for the purpose set forth.

2. The combination of a matrix-frame for an envelop or similar machine having a plurality of adjustable sections, an annulus or ring surrounding and engaging said sections, means for rotating said ring to simultaneously adjust said sections radially thereof to vary the size of the opening in the matrix-frame and adapt it for use with envelops of different sizes, a plurality of folding-flaps situated below the matrix-frame, and means for adjusting said folding-flaps simultaneously with said sections and maintaining them in adjusted position, substantially as described and for the purpose set forth.

3. The combination of a matrix-frame for an envelop or similar machine having a plurality of adjustable sections, an annulus or ring surrounding and engaging said sections, means for rotating said ring to simultaneously adjust said sections radially thereof to vary the size of the opening in the matrix-frame and adapt it for use with envelops of different sizes, a plurality of folding-flaps situated below the matrix-frame, a second annulus or ring situated below the first-men-

tioned ring and surrounding and engaging said folding-flaps and means for rotating said ring to simultaneously adjust said folding-flaps parallel to the edges of the folding-opening, substantially as described and for the purpose set forth.

4. The combination of a matrix-frame for an envelop or similar machine having a plurality of adjustable sections, an annulus or ring surrounding said sections, means for rotating said ring to simultaneously adjust said sections radially thereof to vary the size of the opening in the matrix-frame and adapt it for use with envelops of different sizes, a plurality of folding-flaps situated below the matrix-frame, a second annulus or ring situated below the first-mentioned ring and rigidly connected therewith so as to move together with the adjusting-ring for the frame-sections and to adjust said folding-flaps corresponding to said sections, substantially as described and for the purpose set forth.

5. The combination of a matrix-frame for an envelop or similar machine having a plurality of adjustable sections, an annulus or ring surrounding said sections, an arm or stud projecting from each frame-section and extending radially of said ring, means connecting said ring with each of the arms for moving the frame-sections radially as the ring is rotated, a plurality of folding-flaps situated below the matrix-frame, a second annulus or ring situated below the first-mentioned ring and rigidly connected therewith so as to move together with the adjusting-ring for the frame-sections and to adjust said folding-flaps corresponding to said sections, substantially as described and for the purpose set forth.

6. The combination of a matrix-frame for an envelop or similar machine having a plurality of adjustable sections, an annulus or ring surrounding said sections, an arm or stud projecting from each frame-section and extending radially of said ring, means connecting said ring with each of the arms for moving the frame-sections radially as the ring is rotated, a plurality of folding-flaps situated below the matrix-frame, a second ring situated below the first-mentioned ring and rigidly connected therewith, so as to move together with the said adjusting-ring for the frame-sections and to adjust said folding-flaps corresponding to said sections, an arm or stud projecting from each folding-flap and extending radially of the second ring, means connecting said second ring with each of the arms for moving the flaps radially as said ring is rotated and means for rotating the rings, substantially as described and for the purpose set forth.

7. The combination with a matrix-frame for an envelop or similar machine consisting of a plurality of sections mounted to move relatively to each other, of means for simultaneously adjusting all of said sections to vary the size of the frame-opening, means for adjusting a portion of said sections relative

to the other sections to vary the form of the opening in the frame, of a plurality of folding-flaps mounted to move relatively to each other, means for simultaneously adjusting all 5 of said flaps, to vary the position of said folding-flaps corresponding to the position of the frame-sections, substantially as described and for the purpose set forth.

8. The combination of a matrix-frame for 10 an envelop or similar machine having a plurality of sections mounted to move relatively to each other, a sectional annulus or ring surrounding and engaging all of said sections, means for rotating said ring to simultaneously move all of the frame-sections, means for independently adjusting one of the sections of the ring to adjust the frame-sections connected therewith relative to the other frame-sections, a plurality of folding-flaps mounted to 15 move relatively to each other means for simultaneously adjusting all of said flaps, to vary the position of said folding-flaps corresponding to the position of the frame-sections, substantially as described and for the 20 purpose set forth.

9. The combination of a matrix-frame for 25 an envelop or similar machine having a plurality of sections mounted to move relatively to each other, a sectional annulus or ring surrounding and engaging all of said sections, means for rotating said ring to simultaneously move all of the frame-sections, means for independently adjusting one of the sections of the ring to adjust the frame-sections connected therewith relative to the other frame-sections, a plurality of folding-flaps mounted to 30 move relatively to each other, a sectional annulus or ring surrounding and engaging all of said folding-flaps, means for rotating said 35 ring to simultaneously move all of the folding-flaps, means for independently adjusting one of the sections of the ring to adjust the folding-flaps, connected therewith relative to the other flaps, substantially as described and for the 40 purpose set forth.

10. The combination of a matrix-frame for 45 an envelop or similar machine a series of sections mounted to move relatively to each other, a sectional ring surrounding and engaging said sections, means for rotating said ring to simultaneously adjust all of the frame-sections, means for adjusting either section of the ring independently to move the frame-sections connected therewith relative to the 50 other frame-sections, a series of folding-flaps mounted to move relatively to each other, a sectional ring surrounding and engaging said folding-flaps, means for rotating said ring to simultaneously adjust all of the folding-flaps 55 means for independently adjusting one of the sections of the ring to adjust the folding- 60

flaps, connected therewith relative to the other flaps, substantially as described and for the purpose set forth.

11. The combination of a matrix-frame for 65 an envelop or similar machine having a series of sections mounted to move relatively to each other, a sectional ring surrounding and engaging said sections, means for rotating said ring to simultaneously adjust all of the frame-sections, means for adjusting either section of the ring independently to move the frame-sections connected therewith relative to the other frame-sections a series of folding-flaps mounted to move relatively to each other, a 70 sectional ring surrounding and engaging said folding-flaps, means for rotating said ring to simultaneously adjust all of the folding-flaps, means for adjusting either section of the ring independently to move the folding-flaps connected therewith relative to the other flaps, 75 substantially as described and for the purpose set forth.

12. The combination of a matrix-frame for 80 an envelop or similar machine consisting of a 85 plurality of sections, a sectional annulus or ring surrounding and engaging said sections, means for rotating said ring to simultaneously adjust said sections in the matrix-frame and adapt it for use with envelopes of different 90 sizes, an arm or stud projecting from each frame-section and extending radially of said ring, means connecting said ring with each of the arms for moving the frame-sections radially as the ring is rotated, means for adjusting either section of the ring independently to move the frame-sections connected therewith relative to the other frame-sections, a plurality of folding-flaps situated below the matrix-frame, a second sectional annulus or 95 ring situated below the first-mentioned ring and surrounding and engaging said folding-flaps and rigidly connected with the ring for moving the frame-sections, so as to move together with said ring, an arm or stud projecting from each folding-flap and extending 100 radially of said ring, means connecting said ring with each of the arms for moving the folding-flaps radially and parallel to the edges of the frame-opening, as the ring is rotated 105 and means for adjusting either section of the ring independently to move the folding-flaps connected therewith relative to the other folding-flaps, substantially as described and for the purpose set forth.

In testimony whereof I have signed my name to this specification in the presence of two subscribing witnesses.

ADOLF TELLSCHOW.
